UNITED STATES PATENT OFFICE.

FRANKLIN M. ILER, OF DENVER, COLORADO.

CRUCIBLE-FURNACE.

1,129,983.

Specification of Letters Patent. Patented Mar. 2, 1915.

Application filed May 20, 1912. Serial No. 698,559.

To all whom it may concern:

Be it known that I, FRANKLIN M. ILER, a citizen of the United States, residing at Denver, county of Denver, State of Colorado, have invented certain new and useful 5 Improvements in Crucible-Furnaces, of which the following is a specification.

This invention relates to melting furnaces and more particularly to a hydrocarbon-burning crucible furnace in which metals 10 and their alloys may be melted.

It has been the practice to mix the hydrocarbon fuel, such as oil, gas and the like with a cold air blast coming directly from the 15 blower.

One of the objects of this invention is to pre-heat the air by utilizing the heat conducted through and radiating from the walls of the melting chamber. The pre-heated air mixed with the oil and the like 20 thereby affords a more thorough mixing of the fuel and air and a more complete vaporization of the oil. The arrangement also serves to keep the outer walls of the furnace 25 cool.

Another object is to provide a construction which will facilitate the removal of the crucible while hot and containing a charge of molten metal.

30 Other objects and the novel features of the invention will be apparent from the following description taken in connection with the drawings, in which:

Figure 1 is a plan view of a furnace embodying my improvements, parts being shown in dotted lines. Fig. 2 is a vertical sectional view of the same taken along the line 2-2 of Fig. 1, parts being shown in elevation. Fig. 3 is a vertical sectional view 35 of the same taken along the line 3-3 of Fig. 1. Fig. 4 is a horizontal sectional view of the furnace taken along the line 4-4 of Fig. 3. Fig. 5 is a plan view of a shank or handle employed to lift the crucible from its supporting means in the melting chamber. Fig. 6 is a plan view of a modified 45 form of cover for the furnace. Fig. 7 is a sectional view along line 7-7 of Fig. 6, showing the furnace with the cover applied 50 thereto.

Referring to the drawing, A and B designate two horizontally separable sections which constitute the body of the furnace and the walls of which inclose the melting 55 chamber. The section B constitutes the stationary section or base upon which the sec-

tion A rests when the two are in operative position. The base section B consists of a shell which is cast in one piece and comprises the side wall 10, the bottom 11 and 60 the inwardly extending flange portion 12 at its upper open end. The flange portion 12 has a slight vertically extending projection 13 at its inner edge. The wall 10 is rectangular at one end and has a curved 65 portion 10' at the opposite end which has an opening 14 therein upon which is bolted the cap 15. There is a false bottom 16 integral with the shell which provides an air chamber 17 at the bottom of the base section B. 70 The said chamber is divided longitudinally by a partition 18 also cast integrally with the shell or outer wall of the base section. The wall 10 is provided with a lining 19 of fire-brick, or other refractory material 75 which lines the bottom 16, walls 10 and 10' and flange 12 and is hollowed out at its center to constitute a combustion chamber 20. Within one end of the lining there are two vertical passageways 21 and 22, the 80 passageway 21 extending in the entire height of the lining 19 and opening through the bottom 16 into the air chamber 17 and through the flange 12 into the lining of the upper section A. The passageway 22 also 85 opens through its upper end into the lining of the section A and at its lower end is flared out as at 22' and opens into two concentrically arranged passageways 23 and 24, also in the lining. 90

Upon the cap 15 there is mounted a fuel inlet nozzle 25 which communicates by a pipe P with a tank T containing oil, gas or other fuel under pressure. The said nozzle 25 is mounted on the cap 15, the latter 95 having a lining 26 which forms a connecting passageway 27 between the passageways 23 and 24. To admit air and fuel into the combustion chamber 20 an inlet duct 28 is provided which establishes communication 100 between the passageway 27 and the chamber 20. A plate 29 having an opening 30 therein is seated over the inlet to the duct 28 and partially contracts the area of the inlet. The inner end of the nozzle 25 extends into 105 the duct 28 through said opening 30 and discharges fuel into the same. The duct 28 has one of its walls substantially tangential with the wall of the chamber 20 and is flaring at its inner end. The duct 28 110 constitutes an air and fuel mixing chamber and oil, if used as a fuel, is vaporized there-

in and more thoroughly mixed with the air before the same enters the combustion chamber.

A support or stool 31 of refractory material is removably seated in the combustion chamber 20 on the lining covering the bottom 16. The said stool supports the crucible 32 at its upper end and is of a particular construction to facilitate the removal of the said crucible by means of the shank or handle shown in Fig. 5. The said shank comprises the handle portions 33 and 34 and the crucible engaging portion 35 intermediate the handle portions. The crucible engaging portion 35 has an opening 36 at one side thereof. The said stool 31 is reduced intermediate its ends as at 31' practically at the middle thereof and as shown in Fig. 3 the sides are curved inwardly in longitudinal section. The reduction of the central portion of the stool is for two purposes; first, to increase the size of the combustion chamber 20 and second, to admit the open side 36 of the shank shown in Fig. 5 when the crucible is to be removed. The crucible 32 is provided with a removable cover 32' and is disposed in the crucible chamber 37 within the movable section A.

The crucible chamber 37 and combustion chamber 20 are in axial alinement and when the movable section A rests on the base section B the two sections comprise the melting chamber. The movable section A consists of a shell 38 of sheet or cast metal and has secured at its upper end an annular, inwardly extending cast ring 39 and at the lower end thereof there is an annular cast ring 40 having a downwardly projecting flange 41 at the inner end thereof corresponding with the upwardly extending projection 13 on the member 12. The projections 13 and 14 fit close together and it will be seen that there is thus provided a continuous metal casing for the body of the furnace. The shell 38 of the section A is provided with a lining 42 of fire-brick or refractory material and has the central opening therethrough providing the crucible chamber 37.

Within the walls of the lining 42 there is a spirally arranged air heating passageway 43 which is connected at its upper end to a vertical passageway 44 in alinement with the passageway 21 in the base section B. The lower end of said spiral passageway 43 is connected to a vertical passageway 45 in alinement with the passageway 22 in the base member B. Short threaded nipples 44' and 45' in alinement with the passageways 21 and 22 are screwed into the flange 12 and have tapering edges at their upper ends to more readily aline with the passageways 44 and 45 when the two sections A and B are brought together.

55 A blower F is connected by a pipe P' to

the end wall 10 at 46 and discharges air into the air chamber 17. An upwardly curved portion 16' in advance of the opening 46 deflects the entering air downwardly into said chamber 17. It will thus be seen that for providing air to the combustion chamber there is a continuous channel through the refractory lining and around the melting chamber opening into the combustion chamber 20. The air passing about 75 the melting chamber is not only heated but also keeps the outer wall of the furnace cool and confines the heat to the inner wall and interior of the furnace.

A cast metal cover C is disposed over the 80 open end of the crucible chamber 37. The said cover C comprises a cup-shaped metal casting 47 having a centrally arranged opening 48 therein. The casting 47 is also provided at one side with an integral handle 49 85 and has an integral lug 50 opposite the handle by which it is pivoted to the top casting member 39 at the pivot 51. The casting 47 rests at its lower edge upon the furnace top 39 and has a lining 52 of refractory 90 material forming a continuation of the chamber 37 and having an opening therein in alinement with the opening 48 for the discharge of incombustible gases and the same may also be employed to introduce material 95 to be melted into the crucible 32.

As before stated the top section A is vertically movable and may be moved to such a height that the crucible 32 seated on the support 31 may be withdrawn from between 100 the two sections to pour the charge therefrom. The said section A is provided with plates 53 secured to opposite sides thereof upon which are mounted rollers or trunnions 54. There are two rollers 54 at each side, one at the top and one at the bottom and are revolubly connected to the plates 53 by means of pins 54' screwed into said plates. Vertical grooved standards 55 are bolted to the plate 12 on the bottom section B and 110 extend for a sufficient distance above the said section to allow the section A to be raised above the crucible 32. Extending between the standards 55 above the center thereof is a reinforcing frame 56 which is 115 secured to each of the standards and mounted on said frame 56 is the shaft 57 of a pinion 58 which co-operates with a rack 59 mounted on the rear of the movable top section A. Handles 60 may be provided for operating the pinion 58 to raise and lower the section A.

The rollers or trunnions 54 guide the top section A along the open ended grooves 55' in the guideways 55. The diameter of the rollers 54 is slightly less than the width of the grooves 55'. On account of the fact that the outer unsupported side of the top section A will tend to incline the section 120 slightly out of the vertical there may be 125 130

binding between guideways and trunnions and excessive friction will result. To obviate such a condition the rollers at the top are set to engage the forward edges of the grooves 5 while the lower rollers are disposed to engage the rear edges only. Such a mounting of the movable section replaces excessive sliding friction with rolling friction, greatly improving and simplifying the construction 10 and operation of the furnace.

To hold the movable section A in any desired raised position I have provided counterbalancing means as shown. Cables 61 at opposite sides of the movable section 15 A are secured at one of their ends to ears 62 on said movable section and pass over pulleys 63 and 64 mounted at the upper ends of the guides or tracks 55 and suspended from the outer ends of the cables 61 is a 20 counter weight W. The pulleys 63 and 64 are revolvably mounted in an ear 63' and an arm 64' respectively integral with the guide standards 55 and extending in opposite directions from the upper ends thereof.

From the foregoing description the operation 25 of the device will be apparent. The crucible being in position on its support 31, as shown in Fig. 3, oil or gas is admitted to the combustion chamber 20 under pressure. The air delivered to the chamber 17 will 30 pass through the flues in the lining of the melting chamber and discharge into the duct 28 where the same will be mixed with the gas or vaporized oil, the mixture discharging 35 into the combustion chamber 20. The heat of the chamber walls will be conducted to the walls of the flues and the air passing through will be heated, thereby utilizing waste heat and increasing the intensity and 40 effectiveness of the combustion of the fuel in the combustion chamber.

The charge in the crucible having been melted the movable section A is raised vertically along the guide standards 55 until 45 the bottom thereof is of a sufficient height to clear the top of the crucible. A shank similar to the one shown in Fig. 5 is then employed to remove the crucible for pouring the charge therefrom. By the use of the improved stool the opening 36 in the shank 50 is of the least possible amount, avoiding a weakening of the crucible engaging section 35. The reduced portion 31' of the stool will readily pass through the cut-away opening 36, the handle being held so that the part 35 is inclined and the ends 35' extended 55 down into the combustion chamber 20, thereby presenting the opening 36 to the narrowest part 31' of the stool 31. The enlarged part 35 is then passed up around 60 the crucible near enough to the center thereof to prevent its tipping. The crucible engaged within the part 35 is removed, the molten charge poured therefrom. The 65 crucible is then replaced, and the handle

withdrawn, in readiness to repeat the operation. The counterbalance weight will hold the movable section A in any raised position so that the crucible may be removed and replaced with safety.

Figs. 6 and 7 disclose a modification of the cover shown in Figs. 1 and 3. The latter cover is suitable when the crucible itself is covered as shown. The eddy or suction caused by the escape of the burnt gases 70 through the central opening will not affect the charge in the crucible 32. However, it is frequently desirable to omit the crucible cover in metallurgical work and in melting soft metals such as brass, aluminum, etc. 75 With a crucible open at its upper end it is important that the excessive draft or suction in line with the crucible be avoided so that the said suction will not dislodge any fine powder that might be placed upon the 80 charge of metal for flux or protection.

To eliminate the excessive draft in line 85 with the center of the crucible, the construction shown in Figs. 6 and 7 is provided. The furnace consists of the separable sections as in the form shown in Figs. 2 and 3 having a crucible support or stool 31 in the combustion chamber 20. The said stool 31 supports the open ended crucible 65 which extends up into the heating chamber 37, the 90 upper end of said crucible being in close proximity to the cover of the chamber 37 so that there will be but little space between the two for the passage of gases. The refractory lining 42 supports an annular plate 100 66 at its upper end to which the shell 38 is bolted. By means of pin 67 and a lug 68 having a pivot opening therethrough there is pivoted on the annular plate 66, an annular casting arranged to slide on said plate 105 66 at its lower edge. The said annular casting comprises a rim section 69, forming a retaining means for lining 70 of refractory material, said lining having the same internal diameter as the melting chamber 27.

Inwardly radially projecting goosenecks 71, of which there are three in the present illustration, are cast integral with said rim section 69 and support an integral ring 72 at their lower free ends, the said ring being disposed parallel with the upper edge of the rim section 69. The projection or lug 68 and a handle 73 are also cast integral with the rim section, thereby providing a unitary cover structure. The ring 72 is 110 lined by and supports an annular member 74 of refractory material, the member 74 being held in place by four, more or less, large headed bolts 78, the threaded ends of which engage in threaded holes in the ring 115 72. The member 74 may be formed separately and when secured in place by the bolts, the countersinks are filled with refractory material. The greatest outer diameter of member 74 is less than the inner 120 125 130

diameter of the linings 37 and 70, thereby providing an annular passageway 75 of an outer diameter equal to the diameter of the melting chamber 37. The outer edge of the member 74 is inclined downwardly and inwardly so that the passageway 75 flares downwardly. At its center the member 74 has a circular opening 77 therethrough. The construction as shown in Figs. 6 and 7 10 prevents the eddy or suction which occurs under the other cover and allows the burnt gases to rise straight up and escape through the annular passageway 75. A slight amount of gas will pass over the top and escape through the central opening 77 but not enough to cause an eddy or suction sufficient to dislodge powder in the crucible. By varying the size of the annular passageway 75 a perfect control of the eddy or 15 suction may be effected.

The invention is shown as applied to a crucible furnace utilizing oil as a fuel; it is obvious, however, that features therein may be applied to refining, reduction or 20 other furnaces. In furnaces generally it is advantageous to preheat the air introduced into the combustion or melting chamber and to utilize as much as possible of the waste heat in heating the air. Therefore, in view 25 of the fact that many changes may be made in the details of construction without departing from the spirit of the invention, I do not wish to limit myself to the exact details as shown and described.

30 Having thus described the invention what is claimed as new is:

1. In a furnace, in combination, a melting chamber having a wall of refractory material, a spiral air heating passageway in 35 said wall; an air inlet adjacent the bottom of the wall opening into the spiral passageway at the top; a fuel inlet duct opening into the melting chamber near the bottom, the air heating passageway discharging into 40 said chamber through said duct and mixing therein with said fuel passing into said chamber.

2. In a furnace, the combination of a casting having a wall of refractory material 45 inclosing a melting chamber, said wall comprising separable parts, said parts of the refractory wall having air heating passageways therein which extend longitudinally of said chamber, and means including a duct opening into said chamber for delivering fuel and preheated air to said chamber.

3. In a furnace, in combination, a melting chamber constructed of separable members 50 of refractory material, means for moving one of said members with relation to the other, a continuous air heating passageway extending through the members, an air inlet opening into the passageway, said passageway discharging the heated air into 55 the chamber, and means for mixing fuel

with the air as the latter passes into the chamber.

4. In a furnace, in combination two separable sections constituting a melting chamber, passageways disposed about both sections and connected to one another, an air inlet opening into one of said passageways, a duct connecting one of said passageways with the melting chamber, a crucible in the melting chamber, and means for separating the sections to permit the removal of the crucible.

5. In a furnace, in combination, two separable sections comprising a melting chamber, each of said sections having a lining 80 of refractory material, an air passageway in each lining, said passageway and linings being connected together to form a continuous heating passageway surrounding the melting chamber, air heating passageways 85 in said lining in both sections, said passageways being connected to one another to form a continuous passageway which delivers into said chamber, an air inlet opening into said continuous passageway, means 90 for delivering fuel to the chamber, and means for separating the sections to permit access to the interior thereof.

6. In a furnace, in combination, two separable sections comprising a melting chamber, one of said sections being stationary 95 and another movable, said sections having connected air heating passageways in the walls thereof, and means on the stationary section coöperating with means on the movable section to separate the sections.

7. In a furnace, in combination, two separable sections constituting a melting chamber, the sections being relatively movable and having connected air heating passageways in the walls thereof, means on one of 105 the sections coöperating with means on the other section to separate the same, and means for supporting one of said sections in a position out of contact with the other.

8. In a furnace, the combination of two separable sections comprising a stationary member and a movable member, said sections inclosing a melting chamber when assembled, means comprising a rack on the 110 movable section and a gear on the stationary member for raising the movable member, and means for maintaining the movable member in a raised position.

9. In a furnace, the combination of a suitable body provided with communicating combustion and crucible chambers, a refractory lining for said body and having an air heating passageway therein, a crucible located in the crucible chamber, means 115 mounted in the combustion chamber for supporting the crucible in the crucible chamber, and a tangential passageway communicating with the air heating passageway and opening into said combustion chamber.

10. In a furnace, the combination of a base section comprising a shell lined with refractory material constituting a combustion chamber, a hydrocarbon burner mounted in said shell, an air heating passageway in said lining, means for admitting air to said shell, an air and fuel mixing chamber in the lining opening into the combustion chamber, said passageway and hydrocarbon burner opening into the mixing chamber and a top section and cover supported on and separable from said base section.
11. In a furnace, the combination with a stationary base section, of a vertical guideway thereon, a vertically movable section, means on the movable section coöperating with the guideway to be guided thereby, and means for raising and lowering the movable section.
12. In a furnace, the combination with a stationary base section, of vertical guideways on opposite sides thereof, a vertically movable section, means on the movable section movable along and coöperating with the guideways to be guided thereby, means for raising and lowering the movable section, and means for maintaining the movable section in any desired position along the guideways.
13. In a furnace of the class described, the combination of a furnace comprising two separable parts constituting a combustion chamber and a crucible chamber in axial alinement and having a refractory lining, a crucible located in the crucible chamber, a removable stool mounted in the combustion chamber and adapted to support said crucible in the crucible chamber, and a fuel or gas inlet opening into the combustion chamber tangentially whereby said fuel or gas moves in a swirl about said stool.
14. In a crucible furnace, the combination of a crucible, a two-part casing, means for separating said parts, one part inclosing a combustion chamber and another part inclosing the crucible chamber, a crucible support in the combustion chamber and extending into the crucible chamber, said support being formed with a contracted section to facilitate the removal of the crucible therefrom when said parts are separated.
15. In a crucible furnace, the combination of a crucible, a two-part casing transversely separable and including a stationary section inclosing a combustion chamber and a movable section inclosing a crucible chamber, and a crucible support removably mounted in the stationary section and extending into the movable section, said support having a contracted section intermediate its ends to permit the passage of the support between the ends of a forked member for removing the crucible.
16. In a crucible furnace, the combi-
- nation with a two-part shell comprising a stationary part inclosing a combustion chamber and having a fuel inlet, of a crucible support in said chamber, the sides of which are curved and form a contracted section to facilitate the removal of a crucible from said support.
17. In a crucible furnace, the combination with a two-part shell comprising a stationary part inclosing a combustion chamber and having a fuel inlet and burner, of a removable crucible support therein, the sides of said support being concave and forming a contracted section intermediate the ends thereof, one end extending without said chamber.
18. In a crucible furnace, the combination of a base section, vertical grooved guideways thereon, a movable top section, means thereon engaging in the grooves in the guideways, means mounted on the guideways coöperating with means on the top section to move the latter, a counterbalance weight for maintaining the top section in any desired position, and means for connecting said counterbalance weight to the top section.
19. In a crucible furnace, the combination with a base section, of vertical grooved guideways thereon, pulleys mounted at the upper ends of said guideways, a movable top section coöperating with the base section to form a melting chamber, trunnions on the top section engaging in the grooves of the guideways, a rack on the top section, a pinion and operating means therefor on the guideways, said pinion coöperating with the rack to move the top section vertically, a counterbalance weight for maintaining the top section in any desired position along the guideways, cables having one of their ends connected to the top section and the opposite ends passing over said pulleys and connected to the weight at the ends of the latter.
20. In a crucible furnace, the combination with a base section lined with refractory material, of an air heating passageway in the lining, said lined base section constituting a combustion chamber, means for delivering oil or gas under pressure to said chamber, a top section lined with refractory material, an air heating passageway in the lining thereof, said lined top section constituting a charge containing chamber, said air heating passageways being connected, an air admission inlet for the air heating passageways, said air heating passageway discharging the air flowing therethrough into the path of said oil or gas to be mixed therewith and delivered to the combustion chamber, and an outlet from the charge containing chamber.
21. In a crucible furnace, the combination with a base section lined with refractory material, of an air heating passageway in

- the lining, said lined base section constituting a combustion chamber, means for delivering oil or gas under pressure to said chamber, a vertically movable top section lined with refractory material, a spirally arranged air heating passageway in the lining thereof, said lined top section constituting a charge-containing chamber, said air heating passageways being connected, means 5 for delivering air under pressure to the air heating passageways, said air heating passageways discharging the air flowing therethrough into the path of said oil or gas to be mixed therewith and delivered to the combustion chamber, an outlet from the charge containing chamber, and means for moving said top section vertically.
22. In a furnace, the combination of a wall of refractory material confining a space 10 constituting a melting chamber, said wall having a spiral air heating passageway therein, and extending longitudinally thereof,

said wall having an air inlet near its bottom opening into said passageway, a fuel inlet duct opening into said melting chamber at 25 the bottom, said passageway opening into the duct and the latter constituting a mixing chamber for the fuel and air.

23. In a furnace, a wall of refractory material divided transversely intermediate its 30 ends to form two separable parts, said parts when assembled inclosing a melting chamber, an air heating passageway in said wall, the bottom part of said wall having an air inlet which communicates with said passageway, and a passageway which connects the air-heating passageway with the interior of said chamber.

In testimony whereof I affix my signature in presence of two witnesses.

FRANKLIN M. ILER.
